UNITED STATES PATENT OFFICE.

RHODES ESTELLE, OF LEXINGTON, TEXAS.

MILK-COOLER.

SPECIFICATION forming part of Letters Patent No. 608,113, dated July 26, 1898.

Application filed August 5, 1897. Serial No. 647,226. (No model.)

To all whom it may concern:

Be it known that I, RHODES ESTELLE, a citizen of the United States, residing at Lexington, in the county of Lee and State of Texas, have invented certain new and useful Improvements in Milk-Coolers; and I do declare the following to be a full, clear, and exact description of the invention, such as will enable others skilled in the art to which it appertains to make and use the same.

My invention relates to improvements in milk-coolers; and the object is to provide a simple, effective, inexpensive, and practical device for this purpose.

15 To this end the invention consists in the construction, combination, and arrangement of the several parts of the device, as will be hereinafter more fully described, and particularly pointed out in the claim.

20 In the accompanying drawings the same reference characters indicate the same parts of the invention.

Figure 1 is a perspective view of my improved milk-cooler. Fig. 2 is a vertical section of the same. Fig. 3 is a sectional detail of the upper portion of the water-pail, the textile envelop, the annular ring, and the supporting-hooks. Fig. 4 is a similar view of the butter-receptacle.

25 1 represents an upright provided with a horizontal cross-arm 2, from which depends a suspension-hook 3.

30 4 represents a water pail or bucket suspended by its bail 5 from the hook 3, and the eyes 6 of said bail 5 are rather larger than usual to receive the hooks 7 7 of the parallel rods 8 8, the lower ends of which are formed with hooks 9 9, which extend below the bottom of the pail 4.

35 40 10 10 represent corresponding rods, having their upper hooked ends 11 11 detachably secured to the lower hooked ends of the rods 8 8.

45 12 represents a horizontal cross-bar provided with a central hook 13, and orifices 14 14 are formed in its outer ends to engage the hooks 9 9 on the rods 8 8.

50 15 represents a milk-pail provided with a removable cover 16 and a bail 17, by means of which it is suspended from the hook 13 on the bar 12. A second milk-pail 15' is sus-

pended from a corresponding bar 12', connecting the lower hooked ends of the rods 10' 10', and this arrangement may be continued, so as to include several milk-pails suspended one below the other, as shown.

55

18 represents a cloth sleeve or textile envelop open at both ends and cylindrical in form to encompass the water-bucket 4 and the milk-pails 15 15', and its upper end is provided with an annular textile band 22, forming a circumferential pocket *a* with the sleeve to receive an annular ring 19, having hooks 20 20, which project over the rim of the bucket, while the upper portion 21 of the sleeve is turned inward and downward into the bucket, 60 so as to come in contact with the water.

65 By the well-known principle of capillary attraction the water is diffused over the sleeve, the wet or moist sleeve being in contact with the milk-pails, and as the evaporation of the 70 diffused water takes place on the sleeve the heat incidental to the process is abstracted from the milk, thus considerably reducing its temperature.

75 Other articles than milk may be placed in the pails 15 15', and in the case of butter and other solids the said pails may be perforated to facilitate the cooling process.

It will be observed that the entire weight of the web textile envelop is borne by the 80 ring 19 and the hooks 20, so that the upper portion 21 of the envelop, where it turns over the bucket-rim, is loose to permit free capillary action, which would not be the case if the weight came on the turned-over portion 85 21, which would thus be drawn tight over the bucket-rim, and thus act as a barrier to the capillary action.

Although I have specifically described the construction and relative arrangement of the 90 several elements of my invention, I do not desire to be confined to the same, as such changes or modifications may be made as clearly fall within the scope of my invention without departing from the spirit thereof.

95

Having thus described my invention, what I claim, and desire to secure by Letters Patent, is—

The combination with the water-pail 1 and the milk-pails 15 15', of the textile envelop 18,

100

the annular ring 19 fixed to said envelop and the suspension-hooks 20 fixed to said ring and adapted to engage the rim of the water-pail, whereby the weight of said envelop will be 5 borne by said ring, so that its upper portion 21 will hang loosely within said water-pail, substantially as shown and described.

In testimony whereof I hereunto affix my signature in presence of two witnesses.

RHODES ESTELLE.
